CHECKERWORK CONSTRUCTION

Application filed July 13, 1929. Serial No. 377,975.

This invention relates to a new and improved construction of checkerwork for regenerative purposes, and more particularly to a design especially adapted for use in hot blast stoves.

The invention relates to a design adapted to substantially increase the heat transfer efficiency in checkers and to increase the heating surface in a stove of given size.

10 This invention is in the nature of a modification or improvement of that disclosed in the prior application of Brassert, Hulse and Andrews, Serial No. 247,570, filed January 18, 1928.

15 Hot blast stoves for heating the air for blast furnaces have been constructed with checkerwork of various design. The usual checker employed in this country is built up out of brick placed on edge in such a way as 20 to form square openings. In former years hexagonal brick with round holes were frequently used. Other special shapes have been employed in the past, generally with a view 25 of stiffening the checker column and preventing shifting of the checkers through pressure from the expanding combustion chamber wall, but in every case the checker openings were of the same size from top to bottom and the heating surface was the same in every 30 cross section of the checkerwork throughout the height of the stove, which is usually from eighty to one hundred and ten feet.

35 This uniform construction has the disadvantage that the top checkers do most of the work of heat exchange, both during the period of heating and of giving off heat to the blast. The top checkers are heated to very nearly the same temperature as the combustion chamber, that is, to a bright red heat, 40 and the checkers about thirty feet down are heated to a dull red heat. Below this point the checkers remain black and the lower half of the checker column does but very little work. In other words, the temperature at 45 the top of the checkers is usually around 2000° F., thirty feet down approximately 1200° and fifty feet down about 800°, or very close to the usual chimney temperature of 600°.

50 There are two reasons for the inefficient

work performed by the lower portion of the checkerwork. One reason is that the heat exchange is more rapid and more penetrating the higher the difference in temperature of the heat exchanging mediums. In other 55 words, the heat transfer is a function of the heat head, but it is also a function of the velocity of the gases. When the stove checkers are of equal design all the way through the checker column, the combined open area 60 through the checkers being the same from top to bottom, the velocity of the hot gases is very much greater at the top of the checkers than at the bottom, also the velocity of the cold blast is very much greater at the top of 65 the checkers than at the bottom. If the temperature at the top of the checkers is 2000° and at the bottom 500°, the ratio of velocities is approximately two and one-half to one. In the case of the cold blast, the difference is 70 even greater, being more nearly three to one when high blast temperatures are carried.

We have developed a type of checkerwork which permits of a decrease in the effective 75 passage area for gases in the bottom part of the stove as compared to the top part of the stove, with the result that the velocities may be equalized to whatever extent desired, and a material increase of heating surface obtained. It will be possible to change the 80 effective area through a plurality of steps in the height of the stove. This decrease in effective passage area is caused by the insertion of filler brick in the passages between the main brick and the passages extending 85 through the main checkerbrick. These filler brick, in addition to decreasing the passage area, accomplish a very material increase in the heating surface of the checkers. Filler 90 brick of larger sizes are used in the lower sections to decrease the passage area, and filler brick of progressively smaller area are used in the intermediate and upper sections so that the effective passage area is modified. 95 It will be understood that any desired number of sizes of filler brick may be used, but for purposes of illustration we have shown three such filler brick. The top portion of the stove is preferably formed with no filler 100

brick located in the passages so that at this point the entire passage area is available.

- We have provided octagonal brick having a substantially square interior passageway, the brick being so proportioned that when placed together in a horizontal course the passageways formed between the brick are substantially identical in size and contour, with the passages extending through the brick.
- 5 The octagonal brick are formed with alternate sides of greater and lesser horizontal extent. The sides of greater extent are opposite the sides of the interior passageway and serve to form sides of the pasageways between 10 adjacent brick. The sides of lesser horizontal extent are located outside the corners of the interior passageway and are placed in contact with those of adjacent brick when the checkwork is built up. By this form of construction a maximum contact surface is provided and a construction is formed in which the thickness of the walls between the various 15 passageways is maintained substantially constant.
- 15 One of the difficulties attendant to the use of stoves of this character has been the fact that when vertical passageways are obstructed by the deposit of foreign matter or by spalling or breaking of brick, the entire vertical 20 passage has been lost to the stove, as no means have been provided for the horizontal passage of gases from one vertical passageway to another. In our preferred form of construction we provide notches in ends of certain of 25 the brick, these notches forming passageways so that if a vertical passageway is obstructed at one point it will be possible for gases to use other portions of that passageway by passing from and to adjacent passageways.
- 30 One of the difficulties with this form of construction has been the fact that due to the difference in size or contour between the passages formed between the brick and those passing through the brick, it has been impossible to break joint on the brick horizontally. It has been necessary to have the brick formed in continuous columns throughout the height 35 of the stove. Our form of construction which provides passageways of substantially equal 40 shape and area through and between bricks, permits us to break joint in successive courses and thus thoroughly bond the structure. We also provide means whereby the filler brick 45 may be started at a different level than the main brick so that there is a break of the vertical joints as between filler and main bricks 50 which serves to further bond the structure in this direction.
- 55 It is an object of the present invention to 60 provide a new and improved construction and design of checkbrick and checkerwork.
- 65 It is a further object to provide a construction in which the passageways through and between brick may be similar in size and 70 contour.

It is an additional object to provide means for graduating the effective passage area for gases in the different sections of the stove, and for providing additional heating surface.

It is an additional object to provide checker construction which may be bonded by 75 breaking joint both horizontally and vertically.

It is also an object to provide a checker-brick and construction thereof which will be 80 simple in design and adapted for commercial manufacture and installation.

Other and further objects will appear as the description proceeds.

We have shown certain preferred embodiments of our invention in the accompanying drawings, in which—

Figure 1 is a plan view of the upper portion of a stove taken on line 1—1 of Figure 6;

Figure 2 is a plan view of an intermediate portion of the stove taken on line 2—2 of Figure 6;

Figure 3 is a plan view of a lower intermediate portion taken on line 3—3 of Figure 6;

Figure 4 is a plan view of a lower portion of a stove taken on line 4—4 of Figure 6;

Figure 5 is a plan view of a portion of the supporting structure taken on line 5—5 of Figure 6;

Figure 6 is a diagrammatic fragmentary elevation showing the relation of the various form of brick;

Figure 7 is a fragmentary section taken on line 7—7 of Figure 1; and

Figure 8 is a perspective view of one of the lower supporting members.

Referring first to Figures 1 and 7, the octagonal brick 11 is provided with the wider faces 12 and the narrower faces 13, the narrower faces 13 of adjacent brick contacting with each other. The vertical passageways 14 are formed extending between adjacent brick and also extending through the individual brick. While the passages between brick have square corners, it will be noted that the corners of the passages through the brick have a rounded fillet 15 which is desirable in order to strengthen the brick and prevent their cracking at the corners. This fillet, however, is small and the passages through and between the brick are substantially equal in contour and effective passage area for gases.

As shown in Figure 1, the brick 11 shown in full lines are placed so as to break joints with the brick of the lower courses. This is indicated by the broken lines 16 which show the meeting faces of the lower brick and by the curved lines 17 which indicate the corner fillets on the brick of the lower course which are located below the passageways formed between the brick of the upper course.

As best shown in Figure 7, the brick 11 are provided with the rounded notches 18 formed on their edges on the wider faces 12,

which form sides of the intermediate passageways. These notches 18 are shown as mating on adjacent brick thus forming circular passageways extending transversely between adjacent vertical passages. This provides intercommunication throughout the checkerwork. It will be understood that these transverse passages may be provided on some or all of the brick and may or may not consist of mating notches, as desired. For example, the notches may be only in one end of a brick.

The next lower section of the checkerwork, as shown in Figure 2, consists of the main brick 11 with additional filler brick 19 placed diagonally of the passageways extending both through and between the main brick 11. These filler brick 19 may have rounded ends 20 so that they conform to the fillets 15 of the interior passageways or fit with a slight clearance in the passageways formed between adjacent brick 11. As shown in Figure 2, the brick 19 may be placed at right angles to each other in successive courses. If desired, a number of courses of brick 19 may be placed in one direction with a following number of brick 19 placed in the cross direction. These filler brick provide substantially triangular passageways 21 for the passage of gases.

Figure 3, which shows a lower section of the checkerwork, shows the same main brick 11 and a different type of filler brick 22 placed in the passageways. This brick 22 is similar in general contour to the brick 19 but is provided with the laterally rounded extensions 23 which extend at right angles to the main body of the brick and which, when the brick are placed at right angles to each other in successive courses, as shown in Figure 3, will cause the portions 23 of one brick to overlie the main body portion of the brick below. It will be noted that these brick also form the triangular passageways 21 for passage of gases, these passageways being in direct extension of the passageways 21 shown in Figure 2.

The lower construction shown in Figure 4 includes the same main brick 11 and a filler brick 24 which is in the shape of a cross having arms 25 extending to all four corners of the substantially square passageways. This brick, since it is symmetrical about both axes, can only be placed in the passageways in one position. These brick, however, continue to leave the triangular passages 21 free for passage of gases.

The lower supporting structure is shown in Figure 5 and in the lower portion of Figure 6, together with the filler supporting member 26 which is shown in perspective view in Figure 8. The checkerwork is supported as in the usual construction on arches 27 shown in Figure 6. A layer of rectangular brick 28 is placed across the arches 27

and this layer of brick 28 supports a second layer of brick 29, some of which extend intermediate the arches 27.

It is desirable to have the filler brick 19, 22 and 24 break joint vertically with the main brick 11 and to give this result the 70 filler brick supporting members 26 are provided, these being preferably formed of metal such as cast iron, and being shown in plan view in Figure 5 where they are 75 supported on the upper transverse rectangular brick 29. These supporting members 26 have the meeting surfaces 30 where they fit together to form a laterally supported structure and have the transverse seats 31 80 to support the filler brick. These seats 31 are located at half the height of the members 26. Special brick 32 are provided having chamfered ends 33 to fit together intermediate the supporting member 26, as best 85 shown in Figure 5. These brick 32 are also supported on the upper rectangular brick layer 29. The brick 32 are of the full height of the members 26 which corresponds to the full height of the main checker brick 11. 90 Consequently, when the main brick are placed upon the lower supporting construction shown in Figure 5, these main brick will each be supported upon four of the brick 32 and will also be supported upon the 95 uppermost portions of certain of the members 26. The seat 31 will be located below the bottom of the first layer of brick 11 a distance equal to half the height of such brick, so that the filler brick resting on the 100 seat 31 will extend only half way up into the first layer of brick 11. By continuing this structure upward it will be understood that the filler brick and main brick will break joint vertically throughout the height 105 of the regenerator structure.

By placing the main brick, as shown in Figures 1 to 4, to break joint horizontally, a strong and rigid structure is provided which is interlocked both vertically and 110 horizontally.

Preferably we provide the horizontal openings connecting the vertical passageways in each one of the octagonal brick in the uppermost layer of each intermediate 115 section. For instance in the uppermost section, which usually has no filler brick, we do not need to provide horizontal cross connections. In the uppermost layer of brick of the second section, however, containing 120 the narrowest filler brick, we preferably provide horizontal cross ducts or connections in each of the octagonal brick which are preferably at four points in each brick, as shown in the accompanying drawings. At this 125 point the variation in gas and air velocities from the average which we are striving to maintain, is at its maximum, that is, the velocity of flow in each section is greatest within the top layer. Therefore, it is evi- 130

dently more important to allow the gases to redistribute themselves at this point, in case of the plugging up of one or the other of the vertical flues. Also it is at this point that such plugging up is most likely to occur, on account of the change at this point from a larger to a smaller flue section by the insertion of the filler brick.

The same idea may be followed in the lower sections of the checker column, the cross flues being applied to the top layer of brick in each section. In a balanced draft stove, for instance, of the center combustion Diehl type, more of these cross connections can be applied than in the ordinary side combustion stove, without causing a diagonal flow of the gases toward the flues nearer the exit.

While we have shown certain preferred forms of construction it will be understood that the main and filler brick may be modified somewhat in form and construction, and the supporting members for the filler brick may also be modified and the seat may be located at other portions than half way up the supporting member if it is desired to break the joints at other points. The forms shown are to be understood as illustrative only and we contemplate such changes and modifications as come within the spirit and scope of the appended claims.

We claim

1. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and continuous columns of filler brick placed in said passages to reduce the effective area and increase the heating surface thereof.

2. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and continuous columns of filler brick placed in said passages to reduce the effective area thereof, the filler brick breaking joint vertically with the checker-brick.

3. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in

another layer, and continuous columns of filler brick placed in said passages to reduce the effective area thereof, the filler brick in all passages in any horizontal plane being similar in size and contour whether in or between bricks.

4. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and filler brick placed in said passages to reduce the effective area thereof, the filler brick differing in size at different points in the height of the checkerwork.

5. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and filler brick placed in said passages to reduce the effective area thereof, the filler brick differing in size at different points in the height of the checkerwork and being largest at the bottom portion thereof.

6. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and continuous columns of filler brick placed in said passages to reduce the effective area thereof, certain of the filler brick being placed at an angle to other filler brick in the same passage.

7. A checkerwork construction comprising a plurality of superposed layers of brick, the brick having passages formed therethrough and being placed so as to form passages therebetween, the brick in superposed layers being so placed that the passages through the brick in one layer are in registration with the passages between brick in another layer, and filler brick placed in said passages to locate upper filler brick within the vertical projection of lower filler brick and reduce the effective area thereof, the filler brick being so designed and placed as to leave continuous unobstructed passages throughout the height of the checkerwork.

8. A checkerwork construction comprising a plurality of superposed layers of brick, the brick having passages formed therethrough and being placed so as to form passages therebetween, the brick in superposed layers being so placed that the passages

through the brick in one layer are in registration with the passages between brick in another layer, filler brick placed in said passages to reduce the effective area thereof, the filler brick breaking joint vertically with the checkerbrick, and means at the bottom of the checkerwork to support the lower filler brick at a lower level than the lower checkerbrick.
